UNITED STATES PATENT OFFICE.

RAY H. MANSON, OF ELYRIA, OHIO, ASSIGNEE TO THE GARFORD MANUFACTURING COMPANY, OF ELYRIA, OHIO, A CORPORATION OF OHIO.

SPEEDOMETER.

1,125,702.

Specification of Letters Patent.

Patented Jan. 19, 1915.

Application filed October 12, 1912. Serial No. 725,422.

To all whom it may concern:

Be it known that I, RAY H. MANSON, a citizen of the United States, residing at Elyria, in the county of Lorain and State of Ohio, have invented certain new and useful Improvements in Speedometers; and I do hereby declare the following to be a full, clear, and exact description of the invention, such as will enable others skilled 10 in the art to which it appertains to make and use the same.

My invention relates to speedometers, which are especially adapted for use upon moving vehicles, such as automobiles, motor trucks and the like.

The invention relates to that class of speedometers which employ centrifugally operated means for driving the speed indicating means.

20 I am aware that before my invention balls or similar devices freely moving in channels in a rotating member have been employed in the construction of speedometers, but in such prior devices, so far as I am aware, the balls have either been permitted to move up and down in the channels in one way or another, which permits them to be jostled about when the machine is running over rough roads, thus causing the speedometer 25 indicating means to vibrate and to give an uncertain and inaccurate record, or else slender arms have been employed to restrain the balls. Such arms being slender, they soon become worn away and destroy the accuracy of the instrument.

By my invention, I employ balls or similar devices in the channels in the rotary member, which are restricted to rectilinear motion in a radial direction, any suitable 40 means being provided for preventing their vibrating up and down when the vehicle is in motion. I also prefer to employ in connection with them an annular member, which may engage the balls at different 45 points upon its surface, thus preventing the wearing occurring at any particular point. By this combination, I greatly improve the previous forms of speedometers of this type in accuracy, efficiency and endurance, and make such an instrument successful and practical.

Another object of my invention is to produce a speedometer which can be conven-

iently and cheaply made from standard materials, and with standard tools, enabling me 55 to furnish the public with a better speedometer at a less cost than those of this type hitherto produced.

Another object of my invention is to provide a speedometer of this type, in which 60 the centrifugally operated means are protected from dirt, dust and moisture, and from other foreign matter which tend to destroy the efficiency and accuracy of the instrument.

Other objects of my invention and the invention itself will be better understood from a detailed description of a particular embodiment of my invention, where:—

Figure 1 is a section through the casing, 70 showing the parts of the instrument in elevation. Fig. 2 is a section through the rotary member. Fig. 3 is a plan view of the rotary member. Fig. 4 is a plan view of the parts of the motion transmitting means. 75 Fig. 5 is a rear elevation of parts of the apparatus shown in Fig. 4.

Referring now to the drawing and to the particular embodiment of my invention there illustrated, I show at 6 a casing having a rear wall 7 and side walls 8. A plate of glass or other suitable material 9 is mounted in the front of the casing, and a plate 10, mounted back of the plate 9. The purpose of the plate 10 will be described 85 later.

At 11 I show a rotary member, such as a shaft, which is adapted to be driven through some suitable means, by the object or apparatus whose speed is to be measured. As a 90 general thing in the practice with automobiles to-day, this member is connected by a flexible shaft to a pinion operated by a gear wheel on one of the knuckles of one of the front wheels. The member 11 rotates in a 95 journal box 12, here shown as connected in the casing 6. Ball bearings 13 may be provided, if desired. A second rotary member 14 is here shown mounted upon the top of the shaft 11 and rotates therewith. This 100 member is provided with means for carrying centrifugally operated mechanism, and is here shown as slotted or channeled in a plurality of places 15. In the form shown, there are four of these channels extending 105 radially from the center of the member 11,

and being substantially ninety degrees apart. The bottoms of these channels, and in fact the channels 6 may be perpendicular to the axis about which the member 14 rotates. I prefer to make the bottoms of the channels closed and the tops open. The centrifugally operated means are here shown as balls 16 mounted in these channels to rotate freely therewith and to move in a plane perpendicular to the axis of rotation of the shaft 11 or radially in the channels. I provide means for restricting the longitudinal movement of the balls to this one direction, preventing their vibrating up and down in response to the vibration of the vehicle, which, as can readily be seen, would cause the speed indicating means to vibrate and to give confusing and inaccurate readings. In the form shown, this restraining means consists of shoulders 17 upon the member 14, which part way close the top of the ball containing channels; otherwise these channels are open, as shown at 20, permitting portions of the ball, as shown at 21, to protrude from the channels. Engaging these protruding parts, there is a member 22, which is moved rectilinearly as the member rotates. As will be seen, when the member 14 rotates, the balls 16 will be carried outward by centrifugal force and the protruding parts, engaging the part 22 will elevate it in some way proportional to the speed of rotation of the member 14. The member 22 is an annular member, that is, one which engages the protruding parts of the balls at different surfaces at different times, preventing the wearing away of the surface at any one place and the consequent destruction of the accuracy of the instrument. This will be apparent when it is explained that the accuracy of the instrument depends upon the curvature of the surface of the annular member 22 engaging the balls and of its retaining the curvature originally given to it. I here show this annular member as a cup or saucer shaped member, having a predetermined curve given to its under surface. This curve is determined experimentally, and is shown in the figure. I have found no mathematical equation which describes the curve, and have claimed it as illustrated in the drawing. The sides of the annular member 22 are extended downward, preferably beyond the bottom of the main part of the member 14, protecting the balls and the channels from dirt, moisture and other foreign matter, which enters the speedometer casing, and did it alight upon these parts, would not only tend to impede their operation, but would in time destroy the accuracy of the instrument.

I provide means for guiding the member 22 in the movement imparted to it by the balls, such means being here shown as a pin 25 connected to the member 22, and project-

ing into a slot 26 in the member 14. A second pin 27 is mounted upon the top of the member, constituting a bearing member. Of course, any suitable bearing member may be employed here. This communicates the motion of the member 22 to motion transmitting means which transmits the motion to the speed indicating means. In the form illustrated, the motion transmitting means consists of a bell crank lever 28, one arm 75 29 of which engages the bearing member 27. The bell crank lever is pivoted to the casing at 30 in some suitable way, and the other arm 31 is employed to transmit the motion to the speed indicating means 80 through some suitable mechanism, such as a rack 32 and a pinion 33, which then communicates the motion to the speed indicating means. In the form shown, the pinion 33 is mounted upon a shaft 34, which may 85 be journaled in the frame, and which carries one of the members of the speed indicating means. The speed indicating means indicates accurately or approximately accurately the speed at which the apparatus 90 is running in miles per hour, or in some other suitable units of space in suitable units of time. I here show a rotary member 35, carrying a scale 36 and mounted upon the shaft 34 and rotating therewith. An opening 95 37 is provided in the plate 10 through which the scale may be seen. A marker may be employed upon the edge of this opening, if desired, to indicate the exact speed. Some suitable means is employed for holding the 100 bell crank lever in position against the bearing surface 29. I here employ a spring 40 connected at one end to a lug 41 on the bell crank lever, and at the other end, as shown at 42 to the frame. Suitable means, such 105 as a spring 43 is also employed for holding the rack in position against the pinion. This may be connected at one end to an arm 44 of the bell crank lever.

I will now describe the operation of the 110 device illustrated in the drawing.

When the shaft 11 is rotated, the member 14 will be likewise rotated, and the balls 16 will move outward, exerting a pressure upon the member 22 in proportion to the speed of the member 14. The pressure exerted upon the member 22 will raise the same, and the motion thereof will be communicated to the scale through the bell crank lever, the rack and pinion in a way which will be apparent 115 to those skilled in the art. When the speed is decreased, the force of gravity acting upon the member 22 or the spring 40, or both of them, will move the balls backward 120 in their channels, and the scale will be returned to zero indicating position.

It will be apparent to those skilled in the 125 art that numerous and extensive departures from the form and details of the embodiment here illustrated may be made without 130

departing from the spirit of this invention, this particular embodiment being illustrated solely for the purpose of explaining one of the forms of the invention.

5 I claim:—

1. In a speedometer, the combination with a rotary shaft adapted to be rotated by the object the speed of which is to be measured, a receptacle carried by said member and rotatable therewith, said receptacle having a plurality of radial ball carrying channels cut therein, said channels being perpendicular to said shaft, substantially ninety degrees apart and open at the outside ends, a plurality of balls mounted to rotate and to move longitudinally in said channels, the axis of said balls being unrestrained and the tops projecting beyond the channels and outside the receptacle, lips on the upper walls of the channels to prevent the balls rising therein, a cup-shaped member mounted over said receptacle and covering the top and sides of the same, and the top and ends of the balls resting against the under side of the cup-shaped member, said cup-shaped member being moved upwardly as the balls are moved outwardly in their channels, said receptacle having an axial opening in the top thereof and a pin on the cup-shaped member 30 in said opening guiding said member, a rotary scale and a bell crank lever, rack and pinion for transmitting motion from said cup-shaped member to said scale.
2. In a speedometer, the combination of a rotary member, adapted to be operated by the apparatus, the speed of which is to be measured, said member being provided with a plurality of radially extending channels perpendicular to the axis upon which the rotary member rotates, the sides of said channels being provided with inwardly extending projections forming slots, balls in said channels, the tops of which project through said slots, said projections preventing the balls from rising in said channels, a speed indicating device and means to transmit the motion of said balls to said device.
3. In a speedometer, the combination of a rotary member adapted to be operated by the apparatus, the speed of which is to be measured, said member being provided with a plurality of radially extending channels perpendicular to the axis upon which the rotary member rotates, balls in said channels, the tops of which project above the side walls of the channels, means to prevent the balls rising in said channels, a cup-shaped member resting against the protruding ball tops and adapted to be elevated as the balls move outward, a speed indicating device and means to communicate the motion of the cup-shaped member to the speed indicating device.
4. In a speedometer, the combination of a rotary member adapted to be rotated by

the apparatus, the speed of which is to be measured, said member being provided with a plurality of radial channels, the bottom of the channels being perpendicular to the axis upon which said member rotates, freely moving balls in said channels having their tops projecting above the side walls of the channels, a cup-shaped member mounted over said balls and resting on the tops thereof, said cup-shaped member being raised when said balls move outward, a speed indicating member, and means to communicate the motion of said cup-shaped member to said speed indicating member.

5. In a speedometer, the combination of a rotary member adapted to be rotated by the apparatus the speed of which is to be measured, said member having a plurality of channels therein, balls mounted in said channels and adapted to move therein when said member is rotated, parts of said balls protruding from said channels, means to prevent the balls rising in said channels, a device bearing against the protruding parts of said balls and responding in movement to the movement of said balls, speed indicating means and means to communicate motion from said device to said speed indicating means.

6. In a speedometer, the combination of a rotary member adapted to be rotated by the apparatus the speed of which is to be measured, said member having a plurality of channels therein, said channels being perpendicular to the axis upon which said rotary member rotates, balls mounted in said channels and adapted to move therein when said member is rotated, parts of said balls protruding from said channels, means to prevent the balls rising in said channels, a device bearing against the protruding parts of said balls and responding in movement to the movement of said balls, speed indicating means and means to communicate motion from said device to said speed indicating means.

7. In a speedometer, the combination of a rotary member adapted to be rotated by apparatus the speed of which is to be measured, said member having a plurality of ball carrying channels therein, balls in said channels, means to prevent the balls moving up and down in said channels, an annular member in contact with said balls and responding in movement to the movement of the balls, speed indicating means and means to communicate the motion of said annular member to said speed indicating means.

8. In a speedometer, the combination of a rotary member, adapted to be rotated by apparatus the speed of which is to be measured, movable means carried by said member adapted to move rectilinearly when said member rotates, means restricting the rectilinear motion of said movable means in one

- plane, an annular member responding in movement to movements of said movable member, speed indicating means, and means to transmit motion from said annular member to said speed indicating means. 5
9. In a speedometer, the combination of a rotary member adapted to be rotated by apparatus the speed of which is to be measured, movable means adapted to be moved rectilinearly as said rotary member is rotated, means to restrict the movement of said movable means to a plane perpendicular to the axis upon which said rotary member rotates, an annular member responding in movement to the movement of said movable means, speed indicating means and mechanism for transmitting motion from said annular member to said speed indicating means. 10
- 15 10. In a speedometer, the combination of a rotary member having a plurality of ball carrying channels therein, balls mounted in said channels to move therein, means to restrict the rectilinear movement of said balls to a plane perpendicular to the axis of rotation of the rotary member, a cup-shaped member engaging said balls and moving in response to movements of said balls, speed indicating means and mechanism to transmit motion from said cup-shaped member to said speed indicating means. 20
- 25 11. In a speedometer, the combination of a rotary member having a plurality of radial ball carrying channels therein, said channels being perpendicular to the axis of rotation of said rotary member, balls in said channels adapted to roll along the same, means to restrict the rectilinear movement of said balls to a plane perpendicular to the axis of rotation of said rotary member, a cup-shaped member engaging said balls and adapted to move in response to movements of the balls along the channels, speed indicating means and mechanism to transmit 30 motion from said cup-shaped member to said speed indicating means. 35
- 40 12. In a speedometer, the combination of a revolute member, a plurality of guiding means carried thereby, a plurality of centrifugal members supported by said revolute member and moving in said guiding means, and a reciprocating member having a surface defining a single concavity adapt- 45
- ed to contact with said centrifugal members and to be moved rectilinearly thereby. 55
13. In a speedometer, the combination of a revolute member, a plurality of guiding means carried thereby, a plurality of centrifugal members supported by said revolute member and movable in said guiding means and a rectilinearly movable member having a surface to contact with said centrifugal members, said surface defining a single concavity substantially symmetrical in diametrical section. 60
14. In a speedometer, the combination of a revolute member, a plurality of guiding means carried thereby, a plurality of centrifugal members supported by said revolute member and moving in said guiding means and a rectilinearly movable member having a surface adapted to contact with said centrifugal members, said surface defining a single concavity substantially symmetrical in diametrical section and each 65
- 70 symmetry-half having a portion thereof curved substantially as shown and described. 75
15. In a speedometer, the combination of a revolute member, a plurality of guiding means carried thereby, a cup-shaped member having a surface defining a single concavity, a plurality of centrifugal members supported by said revolute member and moving in the guiding means thereof, said centrifugal members engaging said surface 80 of the cup-shaped member and moving the same rectilinearly when the revolute member is rotated. 85
16. In a speedometer, the combination of a rotatable member and means to rotate the same, a plurality of guiding ways in said rotatable member, centrifugally controlled balls in said ways, a cup-shaped member having an under surface defining a single concavity, said balls engaging said surface 90 and adapted to move said cup-shaped member rectilinearly when the rotatable member is rotated, and means to indicate the movement of said cup-shaped member. 95

In testimony whereof, I affix my signature 100
in the presence of two witnesses.

RAY H. MANSON.
